UNITED STATES PATENT OFFICE.

MERRILL E. CLARK, OF NEW YORK, N. Y.

STABILIZER FOR AEROPLANES.

1,195,977.

Specification of Letters Patent. Patented Aug. 29, 1916.

Application filed February 18, 1914. Serial No. 819,356.

To all whom it may concern:

Be it known that I, MERRILL E. CLARK, a citizen of the United States, residing at New York, in the county and State of New York, have invented a new and useful Improvement in Stabilizers for Aeroplanes, of which the following, taken in connection with the accompanying drawings, is a specification.

10 The present invention involves primarily the construction of improved stabilizing devices adapted for application to any of the usual types of craft designed for aerial navigation; such devices are disclosed in the 15 present instance as applied to the type commercially known as a monoplane, but it will be apparent that it is equally applicable to any and all of the other types of aerial craft, such as biplanes, hydroplanes, etc. 20 The invention contemplates broadly the provision of means, brought into operation at the will of the operator, for resisting any tendency of the machine, while in flight, to plunge, or to tilt about a horizontal axis 25 transverse to the line of flight, and furthermore, the provision of means, brought into action either automatically or at the will of the operator, for resisting any tendency of the machine while in flight, to tilt about an 30 axis substantially parallel to the line of flight. By the coöperation of the instrumentalities above referred to, which are particularly described hereinafter in connection with the accompanying drawings, the dangers 35 resulting from cross currents and rapidly varying conditions of atmospheric pressure, as met with in practical aerial navigation, are effectually eliminated.

Referring to the accompanying drawings, 40 Figure 1 is a side view of an aeroplane equipped with my invention. Fig. 2 is a plan view. Fig. 3 is an enlarged side view of the forward portion of the aeroplane, certain parts thereof being shown in central 45 vertical section for the sake of clearness. Fig. 4 is a side elevation, partly in section, of the apparatus for effecting the automatic operation of a portion of the stabilizing device. Fig. 5 is a section on line 5—5, Fig. 50 4. Fig. 6 is a fragmentary sectional view of parts shown in Fig. 5. Fig. 7 is a plan view of a portion of the apparatus shown in

Fig. 4, certain parts being shown in section on line 7—7, Fig. 3. Figs. 8 and 9 are fragmentary side elevations, looking in the direction of the line of flight of the machine, of one of the stabilizing vanes, in its collapsed and extended positions, respectively. Fig. 10 is a transverse sectional detail view, on line 10—10, Fig. 11, of a valve mechanism for effecting the raising and lowering of one of the stabilizing vanes. Fig. 11 is a longitudinal sectional view of said valve mechanism on line 11—11, Fig. 10.

Similar reference characters refer to similar parts in the different views.

Referring particularly to Figs. 1, 2 and 3, the aeroplane, in the present instance of the monoplane type, comprises a suitably shaped covered framework from which extend the usual suitably curved sustaining planes 1, 1, and which carries the usual alighting and starting gear 2, 2', guiding tail 3, motor 4 and propeller 5, all of which are well known to those skilled in the art, and which form no part of my present invention. In the forward end of the machine, between the motor 4 and a cock pit in which is located a seat 6 for the operator, a vertical mast 7, made hollow for a purpose to be hereinafter described, and extending well above the covered framework, is rotatably mounted. The mast 7 is journaled in an upper bearing 8 carried by the framework, and a smaller tubular member 9 telescoped with said mast 85 and forming an extension of the same, is supported in a thrust bearing 10, which is preferably integral with a lower guy wire post 11 carried by the framework. At its upper end the mast 7 has secured thereto by any suitable means, a vertically disposed stabilizing vane 12, which, in the normal flight of the machine lies substantially in the vertical plane of the line of flight, but which is adapted to be rocked about a vertical axis under certain conditions by the mechanism about to be described. Suitably supported by means of a cradle 13' connecting transverse members A, A, of the frame rearwardly of the mast 7, is a horizontally disposed cylinder 13, Figs. 3, 4, 5 and 7, having its axis transverse to the axis of the aeroplane. The cylinder 13 is closed at its ends, and contains a piston 14, which has a

piston rod 15 extended through a suitable stuffing box 16 carried by one of the heads of the cylinder 13, which rod 15 is supported, near its extreme outer end, in a 5 guide aperture formed in the vertical end 17' of the bracket 17, extending from the cylinder 13. The bracket 17 carries a pin 18 which engages a recess or keyway 19 formed in the rod 15, thereby permitting 10 longitudinal, but preventing rotary movement of said rod. The rod 15 is provided on either side of the vertical support 17' of the bracket with a fixed collar 20, and between each of said collars and the support 15 17' the rod 15 carries a coiled spring 21, said springs being equal in length and of the same strength, whereby to maintain the piston 14 in a position approximately midway the length of the cylinder 13. The frame- 20 work of the aeroplane carries a tank 22 containing compressed air, from which a feed pipe 23 leads to the devices which depend on this medium for their actuation. A branch pipe 24 conveys compressed air from the 25 feed pipe 23 to a horizontal pipe 25 beneath the cylinder 13, Fig. 4, the ends of the pipe 25 opening into oppositely disposed three-way valve casings 26, Fig. 6, each of which has exhaust ports 27, opening to the atmosphere, and cylinder ports 28, which are connected by short lengths of pipe 29 with the interior of cylinder 13, on opposite sides of the piston 14. Each valve casing 26 contains a plug valve 30 provided with a 30 passage 31, which in the position of the valves shown in Fig. 6 connects the compressed air supply with each end of the cylinder 13, thereby maintaining equal pressures on each side of the piston 14, to retain the same in its 35 position midway the length of the cylinder. Each plug valve 30 is provided with a stem 32, extending outwardly therefrom through its respective casing, and to each of said stems 32 is secured a depending arm 33, apertured at its lower end to form guiding and supporting means for a horizontal bar 34 extended through said apertures. Supported in brackets 35, Fig. 5, depending 40 from the transverse members A, A, is a spindle 36 from which is suspended a freely swinging pendulum 37. The pivotal portion of the spindle 36 is constructed to present two opposed rounded shoulders 38 to the opposite faces of the arm of the pendulum, which faces are correspondingly rounded off from the aperture in said arm, as at 45 39, 39, so as to permit of a universal movement of the pendulum about its pivotal point. The upper end of the pendulum arm 50 is expanded into a wide fork 40, embracing the bar 34 and maintained in fixed longitudinal relation thereto by a pair of spaced rods 41 extending transversely of said bar 34 in the same horizontal plane, between which

rods the fork 40 is slidingly held. Immediately outside the guide apertures in the depending arms 33 the bar 34 has secured thereto fixed collars 42, which engage with the arms to rotate one or the other of the plug valves 30 upon longitudinal movement 55 of the bar under the influence of the pendulum 37, as hereinafter described.

The operation of the above described mechanism is as follows:—In the flight of the machine, as long as it maintains its normal upright position, the relation of the several parts of the mechanism is as shown in Figs. 4, 5, 6 and 7. However, if from any cause the machine tips sidewise, about an axis parallel to the line of flight, the 60 influence of the pendulum 37, which is adapted to remain always, by reason of its suspension, in a perpendicular position, brings into action instrumentalities which effect a rotation of the mast 7, and with it 65 the vane 12, in a direction to cause said vane to present a surface in opposition to the resistance of the air in order to right the machine, in the following manner.

Considering Fig. 4, which presents mechanism lying in a substantially vertical plane, transverse to the machine and to the line of flight thereof, assume that the machine tilts sidewise to the right, tending to lower the parts at the right hand end of Fig. 4 and to raise those at the left hand end. The pendulum 37, however, remains perpendicular, whereby the engagement of its upper forked end 40 with the rods 41 moves the bar 34 to the left. The right 100 hand collar 42 on the bar engages the arm 33 of the right hand valve 30 to move the latter in a clockwise direction, causing the passage 31 of said valve to connect the cylinder port 28 of the right hand valve casing 26 with the exhaust port 27 thereof. The left hand valve 30 on the other hand is not actuated by this movement of the bar 34 to the left, since the said bar will merely move through the guide aperture in the depending arm 33 of said valve. The connection thus established between the right hand end of the cylinder and the exhaust port 27 permits the escape of compressed air from said end of the cylinder, whereby 110 the piston 14 moves to the right, by reason of the predominating pressure on its left hand side.

The piston rod 15 has secured thereto a collar carrying an upwardly projecting pin 115 43. The mast 7 carrying the vane 12 is surrounded by a sleeve 44, which is prevented from moving thereon by a pin 45, Fig. 7; and a lever 46 is hinged to said sleeve as at 47, extending rearwardly of the machine 120 and provided with a slot 48 through which the pin 43 is adapted to project. It will be seen that the movement of the piston to

the right, as above described, effects, through the piston rod 15, pin 43 and lever 46, a rotation of the mast 7 and vane 12 to the left, or in a counterclockwise direction, looking down on the machine, whereby the vane 12 is caused to present a surface which will be acted upon by the resistance of the atmosphere to the forward movement of the machine, to restore the machine to its 10 normal vertical position. The righting of the machine as above described, causes the operating devices of the stabilizer vane 12 to resume the positions indicated in Figs. 4, 5, 6 and 7; the pressure previously prevailing in the right hand end of the cylinder 13 is restored, and the piston 14 again moves back to its normal position midway the length of the cylinder owing to the said restoration of pressure and also to the 20 action of the equalizing springs 21, 21. It will be apparent of course, that a tilting of the machine in the other direction will actuate the left hand valve in Fig. 4, causing a movement of the piston 14 to the left, 25 and a swinging of the mast 7 and vane 12 in the opposite direction from that previously described, to effect the righting of the machine.

It will be noted that the pendulum 37 is so suspended that it will perform its function without binding on its pivot, when the aeroplane is pointed upward or downward. Furthermore, the shape of the port openings 27 and 28 of the valve casings and 35 of the passages 31 in the valves is such that a slight movement of the valve cuts off the supply of compressed air from the corresponding end of the cylinder and almost simultaneously connects such end with the atmosphere, and even though the machine tips excessively, causing relatively great movement of the valve, the connection between the cylinder and atmosphere is maintained.

45 The above desirable operation is effected by extending each cylinder port 28 circumferentially of the valve casing as at 28' toward the exhaust port; by correspondingly recessing the adjacent end of the valve passages as at 31'; and by elongating the exhaust ports as at 27'. Furthermore, by means of the hinged connection of the lever 46 with the sleeve 44, it is possible, if desired, to disconnect the mast 7 and the vane 50 12 from the automatic operating mechanism, and rotate the same in either direction by hand, the lever 46 being extended rearwardly of the piston rod 15, in close proximity to the operator, for this purpose.

60 Figs. 3, 8, 9, 10 and 11 illustrate the other elements of the improved stabilizing means, which are designed to resist and correct sudden plunging of the machine, about a horizontal axis transverse to the line of flight.

The pin 45, Figs. 3 and 7, previously referred to, passes through a member 49, which is carried within the telescoped end portion of the member 9 of the hollow mast, and which serves as the head of a cylinder 50 formed by said hollow mast, the other 65 head of said cylinder being formed by member 51, which is provided with a stuffing box of the usual type for the passage of a piston rod 52, carried by a reciprocating piston 53 within the cylinder 50. The piston rod 70 passes loosely through a guide 54 carried at the extreme upper end of the mast 7 and is loosely embraced thereabove by a hub 55, Figs. 3 and 9, carrying oppositely extending 75 arms 56. The end of the piston rod 52 is 80 surmounted by a head 57 to which are pivotally attached a pair of tubes 58, and a pair of tubes 59 are pivotally attached to the upper end of the mast 7, the tubes 58 and 59 85 lying in the same plane as the arms 56. To the outer ends of each arm 56 are pivotally attached a pair of rods 60, which are adapted to telescope into the respective tubes 58 and 59, as clearly shown in Fig. 9. Attached 90 to the tubes 58 and 59 is a silk or canvas vane 95 61 which is held in its extended and taut position in a vertical plane at right angles to the plane of the vane 12, when its framework is in the position shown in Fig. 9, the piston 53 at such time being at the extreme 100 upper limit of its movement in the cylinder 50, as shown in Fig. 3. When the piston 53 is lowered, by the mechanism about to be described, the head 57 is drawn downward, bringing the hub 55 against the guide 54; 105 the rods 60 will be pushed into the tubes 58 and 59 and the entire framework and vane will rest in a collapsed position above the vane 12, as shown in Fig. 8. A branch pipe 110 62, of the compressed air feed pipe 23, is 105 connected upward, as shown in Fig. 3, and connected to one of the ports 63 of a fourway valve casing 64, shown in section in Fig. 10, which is mounted in convenient reach of the operator. The said valve casing 64 is secured to said mast by pipes 65 and 66, which are connected to openings 67 and 68 respectively of said valve casing, and which communicate at their other ends with the 115 interior of the cylinder 50, beyond the upper and lower limits, respectively, of piston travel. Seated within the valve casing 64 is a plug valve 69, having a pair of curved passages therethrough; the one 70, adapted to connect ports 68 and 63 when the valve is 120 turned by a handle 71 into the position shown in Fig. 10 to elevate the piston 53 and distend the vane 61, and the other passage 72, when the valve is in this position, adapted to connect the port 67, in connection with 125 the upper end of the cylinder 50, with a port 73 in the valve casing. The port 73 is in communication with a substantially cylind-

drical bore 74 formed in the valve casing 64, which bore forms a seat for a reciprocating valve 75, normally held in the full line position shown in Fig. 11, by a spring 76, but 5 adapted to assume the dotted line position of said figure when a button 77 on the outer end thereof is pressed inwardly. The bore 74 has a recess 78 in its wall, leading inwardly from the port 73, and diametrically opposite 10 said port 73 and the inner end of said recess 78 the bore is provided with ports 79 and 80 respectively, the one 79, leading to the atmosphere, and the other, 80, in connection with a pipe 81 leading to a small closed tank 15 82 preferably mounted adjacent the air supply tank 22, as shown in Fig. 3. The valve 75 has a diametrical passage 83 connecting ports 73 and 79 in the normal position of the valve. The passage 83 is provided at its 20 end adjacent the port 79 with a longitudinal extension 84 which is long enough to connect the ports 79 and 80 when the valve is in normal position. The coöperation of the 25 two valves 69 and 75 in controlling the movement of the vane 61 is as follows:—It will be noted the two valves can be operated simultaneously, the thumb of the hand which is used to turn the handle 71 being employed to depress the button 77. The 30 upward movement of the piston 53 to extend the vane 61 is accomplished by rocking the valve 69 to bring its passages into the position shown in Fig. 10, with the air supply pipe 62 in connection with the pipe 66 35 leading to the cylinder 50 below piston 53, and with the pipe 65, from above said piston connected with the exhaust passage 73 leading to the open air at 79 when the plug 75 is held out by spring 76 as shown in Fig. 11. 40 This operation extends the vane to its full height. If, however, the plug 75 be pushed in against the tension of the spring 76 when air is to be exhausted from above or below the piston 53, the passage 83 through the 45 plug will be carried out of register with the opening 79 and brought into register with the pipe 81 leading to the closed air tank 82. The volume of the pipe 81 and tank 82 is 50 equal to the volume of the cylinder 50 in which the piston moves. Air will, therefore, flow from one side of the piston 53 into the tank 82 until the piston has assumed a substantially midway position in the cylinder, whereupon the air pressure will become 55 equalized on each side of the piston, bringing the latter to a state of rest, and holding the vane 61 half extended. When it is desired to lower the vane, the valve 69 is turned in the opposite direction, to connect 60 ports 63 and 67 by means of valve passage 72, and ports 68 and 73 by means of the valve passage 70, thereby admitting air above the piston 53 and exhausting air from below said piston.

It will be apparent, that by proper manipulation of the valve 75, that is, by depressing it at varying periods of time after the movement of the valve 69, the vane 61 may be made to assume any desired position intermediate its extreme open and closed positions, whereby the resistance exerted against plunging of the machine may be varied at will. The provision of the two stabilizing vanes actuated as above described greatly minimizes the dangers incident to 65 both endwise and sidewise tipping of the aeroplane; and the utilization of compressed air as a medium for actuating the said devices insures the certain and instantaneous action so greatly to be desired in the operation of safety devices on aeroplanes. It is to be understood that in the normal flight of the machine, the vane 61 is carried in its collapsed position above the vane 12; the mechanism for distending the vane 61 is 70 only brought into operation when the aeroplane exhibits a tendency to plunge.

I claim,

1. In an aeroplane, a hollow mast extending perpendicularly upward above the 90 framework, a vane fixed to said mast, normally disposed in the axis of the line of flight of the machine, a collapsible vane adapted to lie, when distended, in a plane at right angles to the plane of the first vane, 95 means carried within said mast for controlling the distention of said collapsible vane, and means for rotating said mast.

2. In an aeroplane, a vane normally disposed in the plane of the line of flight, a rotatable hollow mast to which said vane is fixed, a movable member within said mast, a second vane secured to said movable member and disposed at right angles to said first vane, means for admitting pressure fluid on 100 opposite sides of said member to control the position of said second vane, a cylinder, a piston within said cylinder having a connection with said mast, and means, responsive to sidewise tipping of the machine, for 105 admitting pressure fluid on opposite side of said piston to rotate said mast.

3. In an aeroplane, a pair of stabilizing vanes normally disposed in planes intersecting at right angles, automatic means for 110 changing the angular disposition of one of said vanes with respect to the line of flight of the machine, and fluid pressure operated means for collapsing and distending the other vane.

4. In an aeroplane, a collapsible vane, a double-acting pressure operated device for causing the collapse and the distention of said vane, a valve controlling the operation of said device, and a second valve supplementing the action of said first valve, for varying the amount of distention of said vane.

5. In an aeroplane, a collapsible vane, a double-acting pressure operated device for causing the collapse and distention of said vane, means for producing a preponderance 5 of pressure on either side of said device to effect the complete collapse or the complete distention of said vane, and means for

equalizing the pressure on opposite sides of said device when said vane is partially collapsed.
